UNITED STATES PATENT OFFICE.

CHAMBERS E. KEMBLE, OF BROOKLYN, NEW YORK.

DESIGN FOR A BODY FOR DRUGGISTS' GRADUATES.

SPECIFICATION forming part of Design No. 27,258, dated June 29, 1897.

Application filed February 2, 1897. Serial No. 621,701. Term of patent 14 years.

To all whom it may concern:

Be it known that I, CHAMBERS E. KEMBLE, a citizen of the United States, residing at Brooklyn, in the county of Kings and State 5 of New York, have invented and produced a new and original Design for the Body of a Druggist's Graduate, of which the following is a specification, reference being had to the accompanying drawing, forming a part there-
of, which represents a perspective view of the body of a graduate embodying the features of my design.

The leading feature of the design consists

of an appendix A at the closed end of the graduate, the said appendix having a spiral 15 ornamentation B.

A further feature of the design consists in an annular flange C, which caps the spiral ornamentation.

I claim—

The design for the body of a druggist's graduate, herein shown and described.

CHAMBERS E. KEMBLE.
